CLAIM

The ornamental design for a diamond whetstone, as shown and described.

DESCRIPTION

FIG. 1 is a perspective view of a diamond whetstone showing my new design;

FIG. 2 is the second perspective view thereof;

FIG. 3 is the third perspective view thereof;

FIG. 4 is the fourth perspective view thereof;

FIG. 5 is a front elevational view thereof;

FIG. 6 is a rear elevational view thereof;

FIG. 7 is a left side view thereof, the right side view being a mirror image of FIG. 7;

FIG. 8 is a top plan view thereof;

FIG. 9 is a bottom plan view thereof;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 1;

FIG. 14 is a partial enlarged view of FIG. 2;

FIG. 15 is a partial enlarged view of FIG. 2;

FIG. 16 is a partial enlarged view of FIG. 2; and,

FIG. 17 is a partial enlarged view of FIG. 2.
